CLAIM

The ornamental design for a building block from a toy building set, as shown and described.

DESCRIPTION

FIG. 1 is a perspective view, from above, of a building block in accordance with the present invention;

FIG. 2 is a perspective view, from below, of the building block of FIG. 1;

FIG. 3 is a front view of the building block of FIGS. 1 and 2, the back and both side views being identical thereto; and, FIG. 4 is a top view of the building block of FIGS. 1-3, the bottom view being identical thereto.

1 Claim, 4 Drawing Sheets
